(57) **CLAIM**

The ornamental design for a Display Mount for a Game Controller, as shown and described.

DESCRIPTION

FIG. 1 is a perspective view of a Display Mount for a Game Controller according to our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof; and

FIG. 8 is the perspective view of FIG. 7, now showing a portion of the mount in an expanded condition.

FIG. 9 is a front perspective view now showing the Display Mount for a Game Controller in its environmental context; and

FIG. 10 is a rear perspective view of FIG. 9.

The dash-dash broken lines illustrate environmental structure and form no part of the claimed design.
